UNITED STATES PATENT OFFICE.

JAMES L. SMITH, OF PRINCETON, INDIANA, ASSIGNOR TO WILLIAM R. WHITE, OF NEOGA, ILLINOIS.

SLIDING GATE.

SPECIFICATION forming part of Letters Patent No. 307,997, dated November 11, 1884.

Application filed June 29, 1883. (No model.)

To all whom it may concern:

Be it known that I, JAMES L. SMITH, of Princeton, in the county of Gibson, in the State of Indiana, have invented a new and useful Improvement in Sliding Gates, which improvement is fully set forth in the following specification, reference being had to the accompanying drawing, which represents a side elevation of the gate.

- 10 This invention relates to that class of gates in which the panel is caused to slide back and forth by the operation of levers extending to positions accessible to the road; and the invention consists of means whereby to transmit the motion from the levers to the gate.

15 The gate consists of a panel, A, of any suitable construction, and is provided with a rail, a, and is supported by suitable wheels or rollers—for instance, friction-rollers—d, on the post H, and a toothed wheel, D, turning on a stud on the post I and gearing with a rack, h, upon the panel.

20 To the wheel D is secured a toothed pinion, b, with which gears a vertically-guided sliding rack, J, the upper end of which is connected in any suitable manner with two levers, K K', pivoted to a cross-piece, L, of the post I. The rack is guided by straps w w upon the post or standard I, and has holes in the

upper end, through which extend fingers v, 30 projecting from the levers K K', and the gate is guided by the rollers d and by a bracket, n, on the post I. By pulling either lever downward at the outer end the rack J is raised, and the tooth-wheels are caused to revolve in an 35 opposite direction, and the gate is closed. A very short motion of the levers will thus serve to open or close the gate. The wheel D is not necessarily a cog-wheel. It may be a friction-wheel or a band-wheel with a strap wound 40 round it and extended at the ends to the opposite ends of the gate and attached thereto.

I claim—

1. The combination, with a sliding gate, of a wheel, D, geared or connected to slide the 45 gate when revolved, a pinion, sliding rack J, and levers pivoted to a standard extending over the road to each side, and connected to operate said rack, substantially as set forth.

2. The panel provided with a rack-bar, h, 50 in combination with the toothed wheel D, pinion b, sliding rack J, and levers K K', substantially as specified.

J. L. SMITH.
